DEHYDROCHLORINATION OF CHLORINATED FATTY ACIDS AND ESTERS

George R. Van Atta, Berkeley, and William C. Dietrich, El Cerrito, Calif., assignors to United States of America as represented by the Secretary of Agriculture

No Drawing. Application April 2, 1947,
Serial No. 738,907

17 Claims. (Cl. 260—405.5)

(Granted under the act of March 3, 1883, as amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to us of any royalty thereon.

This invention relates to the preparation of unsaturated, high-molecular weight, long chain fatty acids and the alkyl esters thereof by the dehydrochlorination of chlorinated, high-molecular weight, long chain fatty acids, particularly those having from 8 to 20 carbon atoms, and the alkyl esters thereof.

The invention has among its objects the provision of a process for the preparation of unsaturated, high molecular weight, long chain fatty acids and the alkyl esters thereof for use in the manufacture of soaps, and of other detergents in which good solubility, wetting power, and free-lathering properties are desired, and also for use in the manufacturing of drying oils and plasticizers. Other objects will be apparent from the description of the invention.

As used herein, the term "dehydrochlorination" means the chemical reaction involving the removal of hydrogen chloride from the molecule of the chlorinated compound. This reaction can be illustrated by the following equations:

1. Dehydrochlorination of monochlorostearic acid

2. Dehydrochlorination of dichlorostearic acid

3. General dehydrochlorination

wherein n may be an integer from 8 to 20, inclusive, x may be an integer from 1 to 4, inclusive, and R represents hydrogen or an alkyl radical.

Methods previously used or proposed for increasing unsaturation in fatty acids through operations upon chlorinated acids or esters may be divided into two main classes, namely,

1. Removal of hydrogen chloride from the liquid chlorinated acid or esters with heat.

2. Treatment of soaps of chlorinated acids with heat in the presence of water.

In the second type of treatment, hydroxylation, as well as unsaturation, can occur.

Distinction between variations of these two methods has rested in the past upon choice of chlorinating agent, or alkali, diluents, and materials to absorb or react with the hydrogen chloride evolved. Although various temperatures and pressures have been employed, there has been apparently no attempt to vaporize completely the

2

chlorinated long-chain fatty materials and to accomplish unsaturation while the materials are in the vapor phase.

We have found that it is not practicable to dehydrochlorinate chlorinated fatty acids or their esters by heating the liquid materials at atmospheric pressure. For example, in periods of heating at 200° C. for 8 to 15 hours in an inert atmosphere and under strong agitation, only about half the chlorine was removed from chlorinated palmitic acid which originally contained between 21.5 and 22 percent of chlorine. Moreover, such long periods of heating appeared to encourage undesired side reactions, and at least the bulk of the remaining chlorine appeared to be held no more firmly than that removed earlier in the process, since further quantities could be removed by continued heating under the same conditions. Further evidence of this progressive decomposition is observed when attempts are made to free the products of their very dark color by vacuum distillation. Substantially all the combined chlorine must be removed from such materials if clear, pale, and stable products are to be obtained by vacuum distillation.

Dehydrochlorination is promoted by raising the temperature of the chlorinated material, but other reactions leading to the decomposition of the unsaturated residue are also encouraged by heating. The effect of these latter reactions becomes excessive if attempts are made to effect substantially complete dehydrochlorination by increasing treatment temperature alone.

Reduction of pressure favors dehydrochlorination in accordance with the law of mass action, but so long as the chlorinated fatty material remains liquid the process is slow and the other disadvantages mentioned persist.

It has now been found, however, that if the dehydrochlorination is conducted in the presence of a dehydrochlorination catalyst and under conditions of temperature and reduced pressure such that the reaction takes place in the vapor phase,

separation of hydrogen chloride from the molecules of chlorinated fatty material is greatly accelerated and at the same time other types of decomposition favored by either prolonged heating or very high temperature are minimized. It was found that the catalyst has the specific effect of increasing the rate of hydrogen chloride removed, and hence, products of a high degree of unsaturation are obtained within a very short period of treatment.

It is preferred that dehydrochlorination be conducted at a temperature of about from 220° to 300° C. and at a pressure of less than about 5 mm. of mercury, and more preferably at a pres-

3
sure less than about 2 mm. of Hg to minimize formation of polymers.

Accordingly, a further object of this invention is therefore the provision of a method for dehydrochlorinating chlorinated fatty acids or esters in vapor phase in the presence of a dehydrochlorination catalyst.

In the process described herein, unsaturation is produced in chlorinated fatty acids or their esters by heating them in the presence of a dehydrochlorination catalyst and in the absence of air to a temperature above that at which they boil under the reduced pressure employed. It is necessary to maintain the reacting materials in the vapor phase for only a very brief period in order to effect substantially complete dehydrochlorination of the chlorinated fatty materials. After this short period (about 0.01 to 5 seconds) of heating, the vapors, still under reduced pressure, are cooled promptly to such a temperature that substantially all their organic components are condensed to liquid. The hydrogen chloride, which after cooling remains in the gaseous phase, is withdrawn by suction to be separately recovered or disposed of as desired.

The process herein described and claimed is an extension and improvement of the process set forth in the application of George R. Van Atta and David F. Houston, Serial No. 549,082, filed August 11, 1944, now Patent No. 2,430,897.

By processing in the manner outlined above, the following ends are achieved:

1. Vapor-phase dehydrochlorination is accomplished in a very brief period of heating, in contrast to the prolonged treatment necessary in liquid-phase operation.

2. Besides effecting an economy in time, the short period of heating lessens opportunity for formation of undesired products of side reactions.

3. Dehydrochlorination is carried far beyond the limits practicable in liquid-phase operations performed on the free acids or esters.

4. Clear, pale-colored unsaturated products, which are stable with respect to color and chlorine content, are obtained directly. The alkali soaps of these products are excellent detergents, resembling coconut-oil soaps in solubility and in emulsifying, lathering, and wetting power.

5. Vapor-phase dehydrochlorination, being conducted in the absence of air, avoids unwanted oxidation during heat treatment.

6. Since dehydrochlorination is effected without the addition of reagents or diluents, their cost is avoided, and the products are obtained without contamination.

7. Vapor-phase dehydrochlorination, in contrast to other methods, is especially suited to continuous-type operations with their characteristic opportunities for cost economies.

8. Dehydrochlorination is effected without hydroxylation. In processes involving use of water and alkali, hydroxy compounds are formed in variable quantity.

9. Use of the catalyst causes more rapid dehydrochlorination and gives a product containing a higher degree of unsaturation. Further, use of the catalyst permits employment of lower temperatures whereby side reactions are minimized.

In accordance with this invention, high molecular weight chlorinated fatty acids or their esters, particularly those having from 8 to 20 carbon atoms, are fed, in the vapor state, at controlled rates into a heated dehydrochlorination catalyst-packed, and evacuated reaction cham-

ber. Disruption of the chlorinated material begins immediately and continues during the very brief interval required for the vapors to traverse the chamber to the outlet under the influence of suction. Upon emerging from the reaction chamber the vapors enter a heat exchanger, where the now unsaturated fatty material is condensed to a liquid by cooling.

From the heat exchanger, the liquefied product flows into receiving vessels. During continuous operations, the stream of product is directed by means of valves alternately into one and another of the collectors. This permits withdrawal of the product from the collectors as they become filled without interrupting the dehydrochlorination process.

The hydrogen chloride remains in the vapor phase and passes from the heat exchanger through an outlet under the influence of suction.

Design of the dehydrochlorination equipment, selection of mechanical accessories, and position of the various parts of the apparatus are matters in which wide freedom of choice may be exercised. In one of the forms of the apparatus 20 that has proved convenient, a U-shaped tube was immersed in a heated oil bath. The chlorinated material is introduced into one leg of the tube which acts as an evaporator. The other leg of the tube is packed with the dehydrochlorination catalyst, and this latter leg acts as the reaction chamber. The last-mentioned leg of the tube is attached to a source of vacuum through a condenser.

Another form of apparatus was better adapted 35 to larger scale operation. In this device the reaction chamber consisted of a vertical glass tube packed with the dehydrochlorination catalyst and surrounded by an electrical heating device. The reaction tube was connected at its lower end to a preheating tube which served to vaporize chlorinated material entering the system. The vapors of chlorinated material pass up through the reaction tube and are then led into a condenser where the product is cooled to a liquid and removed from the system while the vapors of hydrogen chloride pass through the condenser to a scrubber which removes any small traces of organic product that may have escaped condensation.

50 Considerable latitude in choosing the materials to be used for constructing the dehydrochlorinator is also permissible. Thus, for example, in various satisfactory forms of the apparatus, reaction chambers and condensers have been of glass, porcelain, and stainless steel tubings.

It has been found that various solid, inorganic catalysts, which may be termed "dehydrochlorination catalysts," were found to be effective. Such applicable catalysts include the elemental metals iron, nickel, cobalt, uranium, vanadium, thorium, chromium, titanium, cerium, tungsten, and silver, the inorganic compounds of these metals, such as ferric oxide, nickel oxides, cobalt oxides, cobalt chlorides, cobalt phosphates, uranium oxides (UO_2 and UO_3), vanadium oxides, thorium oxides, chromium oxides, titanium oxides, cerium oxides, tungsten oxides, silver vanadate, ferric chloride, nickel chlorides, chromium chlorides, ferric phosphate, nickel phosphate, and so forth, and mixtures thereof. Thus, for example, carbon-steel wool or stainless-steel (a chromium-nickel steel alloy) wool can be used as the catalyst.

It was observed that materials of especially 75 high degree of unsaturation were obtained by

the use of cobaltous-cobaltic oxide (Co_3O_4); cobaltous chloride; cobaltous phosphate; a mixture of 75 percent cobaltous-cobaltic oxide and 25 percent uranium trioxide; a mixture of 75 percent cobaltous phosphate and 25 percent uranium phosphate; and a mixture of cobalt pyrophosphate, cobaltous oxide and cobaltous-cobaltic oxide. It has been found that especially good results are obtained when both a weak and a strong catalyst are used in conjunction. The two types of catalysts are arranged in separate zones, so arranged that the incoming vapors first contact the weak catalyst and then the strong catalyst. In this way, polymer formation is diminished and the channels through the catalyst are not plugged with resinous by-products. It has been found that, for the weak portion of the catalyst, it is preferred to use one of the metals or alloys referred to above in a form having extended surface, i. e., in the form of screen, mesh, gratings, turnings, wool, and so forth. In particular, we prefer to employ in this connection stainless-steel (a chromium-nickel steel alloy) screen in the form of small U-shaped pieces. For the strong catalyst, any of the aforementioned cobalt compounds may be used.

Preferably, the catalysts are supported on a suitable carrier such as pumice, silica gel, active carbon, silicon carbide, coke, and so forth.

The following examples disclose the method of operation, and it is to be understood that these examples are given by way of illustration, and not limitation.

EXAMPLE I

USE OF STAINLESS-STEEL WOOL AS CATALYST

Purified palmitic acid was chlorinated at 70° C. until approximately two equivalents of chlorine had been substituted per equivalent of acid. The product containing mono-, di-, and poly-chlorinated palmitic acids, as well as some unchanged palmitic acid, had a chlorine content of 22.6 percent (theoretical chlorine content of dichloropalmitic acid is 21.8 percent).

A U-shaped tube was immersed in a heated oil bath. The chlorinated acid was fed into one leg of the tube at the rate of 3 grams per hour. The other leg of the tube was packed with 5.5 cm. of 18-8 stainless-steel wool (an alloy containing 18 percent chromium and 8 percent nickel), and this leg was connected through a condenser with a vacuum pump. The temperature of the oil bath was maintained at about 220° C., while the pressure in the condenser was held at slightly less than 1 mm. The chlorinated acid fed into the first leg of the tube was vaporized because of the high temperature and low pressure and the vapors passed upwardly through the catalyst column where the dehydrochlorination took place. The vapors leaving the catalyst zone were cooled and the unsaturated acids condensed. Wijs iodine value of the condensed product was taken as the index of its unsaturation. The product in this instance had an iodine value of 81.1.

EXAMPLE II

COMPARISON OF DIFFERENT CATALYSTS

The process of Example I was repeated, employing different catalysts for the purpose of comparing their effects, but using the same starting material and the same apparatus and conditions as set forth in Example I. In each run, the reaction leg of the U-tube was packed with 5.5 cm. of the particular catalyst under test.

Granules of pumice (2-3 mm.) were used to support the trial catalysts in most instances. Runs were also made with no catalyst and with glass wool and pumice for purposes of comparison.

The results obtained are shown in the following table:

TABLE I

Tests of various substances as dehydrochlorination catalysts for dichlorinated palmitic acid at 220° C. and 1 mm. pressure

Trial catalyst	Support	Wijs iodine value of product
None ¹	None	3.1
Glass wool ¹	do	6.6
Granular pumice ¹	do	23.6
Carbon-steel wool	do	44.5
Fe_2O_3	Granular pumice	56.8
NiO	do	61.2
Co_3O_4	do	106.0
$CoCl_2$	do	128.0
$Co_3(PO_4)_2$	do	135.7

¹ These runs do not illustrate the process of the invention, but are included only for purposes of comparison.

Referring to the above table, no catalyst was used in the first run. As evident from the low iodine value of the product, only a very slight degree of dehydrochlorination took place. The next two runs show that glass wool and granular pumice have little catalytic value. The best results were obtained with the cobalt compounds, particularly with cobalt chloride and cobalt phosphate.

EXAMPLE III

An apparatus was set up which was adapted to larger-scale operations. The reaction chamber was a vertical glass tube in which the lower 10.5 cm. portion was packed with stainless-steel screen (a chromium-nickel ferrous alloy) and the upper 26.5 cm. portion packed with cobaltous chloride-pumice catalyst. This reaction tube was surrounded by an electrical heating apparatus. The reaction tube was connected at its lower end to a preheating tube which served to vaporize the chlorinated acid entering the system. The chlorinated acid vapors then passed up the reaction tube, contacting first the stainless steel and then the cobaltous chloride-pumice catalyst. The vapors issuing from the upper part of the reaction tube were passed into a condenser.

The dichlorinated palmitic acid (prepared as described in Example I) was fed into the system at the rate of 0.5 gram per minute, the catalyst chamber being maintained at about 270° C. and the pressure being maintained at about 3.2 mm. of mercury. The estimated linear velocity of the feed vapor entering the catalyst-packed zone was about 200 cm. per second, while the velocity of the vapors just before leaving the catalyst was about 2,700 cm. per second. It was found that filling the lower 10.5 cm. of the catalyst tube with U-shaped bits of punched stainless-steel screen had the effect of decreasing polymer formation. Stainless steel apparently operates as a weaker catalyst, and when the vapors first contact the weaker catalyst before striking the stronger catalyst, the formation of polymers is drastically reduced. The dimensions of the granules of cobaltous chloride-pumice catalyst used to fill the upper 26.5 cm. of the tube were about 9-11 mm.

A total of 142.6 grams of chlorinated acid was fed into the system and 108 grams of unsaturated product obtained, i. e., 96.7 percent of theory. The product had a chlorine content of 3.30 percent and an iodine value (Wijs) of 138.8.

EXAMPLE IV

A series of experiments was carried out, using the apparatus described in Example III. In each case di-chlorinated palmitic acid (prepared as described in Example I) was fed into the system at the rate of 0.5 gram per minute. In all the experiments except No. 1, the catalyst tube was packed with stainless-steel screen and cobaltous chloride-pumice catalyst as described in Example III. In experiment No. 1, the catalyst tube was packed with 26 cm. of the cobaltous chloride-pumice catalyst alone. The catalyst used in experiment No. 5 was previously employed in experiment No. 4. In experiment No. 7, the pumice used for preparing the catalyst was digested in hydrochloric acid, washed free of acid, and dried before impregnation with cobaltous chloride.

The following table sets forth the conditions of operation and the results obtained:

TABLE II

	Experiment No.						
	1	2	3	4	5	6	7
Pressure, mm. Hg.	0.7	0.9	1.3	0.25	0.5	0.5	0.3
Temperature, degrees C.	315	295	290	260	275	275	275
Chlorine in product, per cent	2.87	3.03	3.80	3.90	7.03	3.15	2.40
Feed weight, g.	177.8	71.9	32.5	145.4	183.8	178.4	141.7
Product weight, g.	119.2	55.6	25.7	114.6	148.6	138.3	108.5
Product recovered, per cent of theory	84.8	97.6	99.2	98.6	98.0	97.8	97.2
Iodine value of product (Wijs)				120.0		124.5	132.9

¹ In this experiment cobaltous-chloride catalyst was used alone. The lower yield indicates greater polymer formation when the single catalyst is used in comparison with the other experiments when the dual catalyst was employed.

The unsaturated products were clear, pale orange-colored liquids at slightly above room temperature. At room temperature they partially crystallized. They showed no tendency to discolor with age when protected from oxygen and mineral acids.

EXAMPLE V

DEHYDROCHLORINATION OF CHLORINATED OLEIC ACID

A 0.9 N solution of chlorine in methylene chloride, cooled to about -20° C., was slowly poured into a 10 percent solution of pure oleic acid in the

same solvent at the same temperature. The temperature of the mixture was not allowed to rise above -8° C. during the addition. The quantity of chlorine added was limited to 95 percent of the amount required for saturation of the oleic acid. After mixing, the solution was purged of chlorine by bubbling a stream of nitrogen through it. The chlorinated acid was recovered by distillation under reduced pressure. The chlorinated product contained 18 percent chlorine and had an iodine value of 9.6. The product contained 87 mol percent 9,10-dichlorostearic acid and 13 mol percent of oleic acid.

The chlorinated acid was dehydrochlorinated in the apparatus described in Example III, utilizing the stainless-steel screen and cobaltous chloride-pumice dual catalyst as described therein. The chlorinated acid was fed into the system at the rate of 0.5 gram per minute. The temperature and pressure were maintained at about 270° C. and about 1.3 mm., respectively. The product contained 3.1 percent of chlorine and was obtained in a yield of 75.5 percent. The iodine value of the product (Wijs) was 96.3.

EXAMPLE VI

Gaseous chlorine was introduced into palmitic acid at 70° C. The product contained 36.8 percent chlorine (theoretical for tetrachloro palmitic acid 35.98 percent).

The chlorinated acid was dehydrochlorinated in the apparatus described in Example III, utilizing the stainless-steel screen and cobaltous chloride-pumice dual catalyst as described therein. The raw material was fed into the system at the rate of 0.5 gram per minute. The temperature and pressure were maintained at about 280° C. and about 1.3 mm., respectively. The product contained 8.4 percent chlorine and was obtained in a yield of 70.4 percent. The iodine value (Wijs) of the product was 157.7.

EXAMPLE VII

A series of experiments were carried out, employing the apparatus described in Example I. The chlorinated materials were fed into the system at the rate of 3 grams per hour. The reaction leg of the tube was filled with 5.5 cm. of the cobaltous chloride-pumice catalyst. The results are disclosed in the following table.

TABLE III

Starting material	Experiment No.				
	1	2	3	4	5
Chlorin-ated stearic acid ¹	20.1	22.1	21.6	18.1	30.7
Chlorin-ated palmitic acid ²	1.0	1.0	1.0	1.0	1.1
Chlorin-ated methyl palmitate ³	240	220	220	220	285
Chlorin-ated palmitic acid ⁴	0.7	1.5	11.5	1.4	2.4
Chlorin-ated linoleic acid ⁵	80.0	88.0	93.0	85.0	55.0
Iodine value of product (Wijs)	131.6	130.2	81.3	134.6	139.4

¹ The chlorinated stearic acid (Exp. No. 1) was prepared by direct chlorination of purified stearic acid. The chlorinated acid contained 20.1% chlorine (theoretical for dichlorostearic acid, 29.07%).

² The chlorinated palmitic acid (Exp. No. 2) was prepared as in Example I; it contained 22.1% chlorine (theoretical for dichloropalmitic acid, 21.8%).

³ The chlorinated methyl palmitate (Exp. No. 3) was prepared by direct chlorination of purified methyl palmitate at 40° to 50° C. The chlorinated ester contained 21.6% chlorine (theoretical for methyl dichloropalmitate, 20.9%).

⁴ The chlorinated palmitic acid (Exp. No. 4) was prepared by saponification of the chlorinated methyl palmitate described above (footnote 3).

⁵ The chlorinated linoleic acid (Exp. No. 5) was obtained by chlorinating linoleic acid obtained from sunflower-seed oil fatty acids. The same chlorination technique was used as in connection with oleic acid (Example V). The chlorinated acid had an iodine value of 4.6 and a chlorine content of 30.7 (theoretical for tetrachlorostearic acid, 33.59%).

⁶ The reported yields in these experiments are estimated to be from 5 to 15% lower than actual because of product "hold-up" in the apparatus.

The process of the invention can be applied to a wide range of chlorinated acids and esters to obtain unsaturated products. Thus, the process can be applied to mono-, di-, or polychlorinated fatty acids having from 8 to 20 carbon atoms or their esters with short chain alcohols. Thus, use can be made of the mono-, di-, or polychlorinated derivatives of caprylic, pelargonic, capric, undecylic, lauric, tridecylic, myristic, pentadecylic, palmitic, stearic, margaric, nondecylic, arachidic, oleic, undecylenic, elaidic, ricinoleic, palmitoleic, erucic, brassidic, and linoleic acids.

In addition to the chlorinated fatty acids, the process can be applied to the short chain alkyl esters of the chlorinated fatty acids. It has been found that the methyl and ethyl esters of the chlorinated fatty acids give results most nearly comparable with those obtained with the chlorinated fatty acids themselves. Mixtures of chlorinated fatty acids or chlorinated fatty acid esters also can be used.

Some particular materials which are particularly adapted to be used are listed below, although it is to be emphasized that these examples are given by way of illustration and not limitation, i. e., monochlorinated palmitic acid, dichlorinated palmitic acid, trichlorinated palmitic acid, tetrachlorinated palmitic acid, monochlorinated methyl palmitate, dichlorinated methyl palmitate, trichlorinated methyl palmitate, tetrachlorinated methyl palmitate, monochlorinated ethyl palmitate, dichlorinated ethyl palmitate, trichlorinated ethyl palmitate, tetrachlorinated ethyl palmitate, monochlorinated stearic acid, dichlorinated stearic acid, trichlorinated stearic acid, tetrachlorinated stearic acid, monochlorinated methyl stearate, dichlorinated methyl stearate, trichlorinated methyl stearate, tetrachlorinated methyl stearate, monochlorinated ethyl stearate, dichlorinated ethyl stearate, trichlorinated ethyl stearate, tetrachlorinated ethyl stearate, monochlorinated arachidic acid, dichlorinated arachidic acid, trichlorinated arachidic acid, tetrachlorinated arachidic acid, monochlorinated methyl arachidate, dichlorinated methyl arachidate, tetrachlorinated methyl arachidate, monochlorinated ethyl arachidate, dichlorinated ethyl arachidate, trichlorinated ethyl arachidate, tetrachlorinated ethyl arachidate, monochlorinated oleic acid, dichlorinated oleic acid, trichlorinated oleic acid, tetrachlorinated oleic acid, monochlorinated methyl oleate, dichlorinated methyl oleate, trichlorinated methyl oleate, monochlorinated ethyl oleate, dichlorinated ethyl oleate, trichlorinated ethyl oleate, tetrachlorinated ethyl oleate. Likewise, the corresponding mono-, di-, tri-, and tetrachlorinated derivatives of other fatty acids such as caprylic, pelargonic, capric, undecylic, lauric, tridecylic, myristic, pentadecylic, margaric, nondecylic, undecylenic, elaidic, ricinoleic, palmitoleic, erucic, brassidic, linoleic, and so forth, can be used as well as the corresponding methyl and ethyl esters. Mixtures of these chlorinated fatty acids, mixtures of these chlorinated fatty acid esters, or mixtures of both can be used.

These compounds listed above are not necessarily pure, individual compounds, but they may have an average composition represented by their names. Thus, "monochlorinated stearic acid" refers to either the individual compound or the mixture of isomers prepared by reacting chlorine with stearic acid until the product contains an average of one atom of chlorine per stearic acid

molecule. This method of chlorinating acids is preferred because it is simple, economical, and gives good results. It is possible, of course, to use particular individual chlorinated compounds. Thus, by reacting oleic acid with chlorine under mild conditions to obtain only addition, 9,10-dichlorostearic acid, an individual compound is prepared. Other individual compounds of this type which may be used are methyl 9,10-dichlorostearate, ethyl 9,10-dichlorostearate, 9, 10, 12,13-tetrachlorostearic acid (by chlorination of linoleic acid), methyl 9,10,12,13-tetrachlorostearate, 2-chloropalmitic acid, 2,3-dichloropalmitic acid, 2-chlorostearic acid, 2,3-dichlorostearic acid, and so forth.

Further, it is not necessary to use purified or individual fatty acids. The mixtures of homologous fatty acids obtainable in commerce by the hydrolysis of natural fats and oils are very useful. Thus, one may chlorinate the mixture of fatty acids obtained by hydrolyzing coconut oil, palm-kernel oil, tallow, suet, cottonseed oil, peanut oil, lard, olive oil, whale oil, sardine oil, corn oil, soybean oil, and so forth. Thus, one may employ monochlorinated coconut fatty acids, dichlorinated coconut fatty acids, trichlorinated coconut fatty acids, monochlorinated palm kernel fatty acids, dichlorinated palm kernel fatty acids, trichlorinated palm kernel fatty acids, tetrachlorinated palm kernel fatty acids, monochlorinated tallow fatty acids, dichlorinated tallow fatty acids, trichlorinated tallow fatty acids, tetrachlorinated tallow fatty acids, monochlorinated suet fatty acids, dichlorinated suet fatty acids, trichlorinated suet fatty acids, monochlorinated cottonseed fatty acids, dichlorinated cottonseed fatty acids, trichlorinated cottonseed fatty acids, monochlorinated peanut fatty acids, dichlorinated peanut fatty acids, trichlorinated peanut fatty acids, tetrachlorinated peanut fatty acids, monochlorinated lard fatty acids, dichlorinated lard fatty acids, trichlorinated lard fatty acids, monochlorinated soybean oil fatty acids, dichlorinated soybean oil fatty acids, trichlorinated soybean oil fatty acids, monochlorinated olive oil fatty acids, dichlorinated olive oil fatty acids, trichlorinated olive oil fatty acids, tetrachlorinated olive oil fatty acids, monochlorinated whale oil fatty acids, dichlorinated whale oil fatty acids, trichlorinated whale oil fatty acids, tetrachlorinated whale oil fatty acids, monochlorinated sardine oil fatty acids, dichlorinated sardine oil fatty acids, trichlorinated sardine oil fatty acids, tetrachlorinated sardine oil fatty acids, monochlorinated corn oil fatty acids, dichlorinated corn oil fatty acids, trichlorinated corn oil fatty acids, tetrachlorinated corn oil fatty acids. In this manner, highly unsaturated fatty acids can be prepared from cheap raw materials by a simple and economical process. By the technique of this invention, a double bond is introduced for each chlorine atom present. Thus, if the starting material contains one chlorine atom per molecule, the product will contain one double bond; if the starting material contains two chlorine atoms per molecule, the product will contain two double bonds, and so forth. The amount of chlorine introduced depends on what type of product is desired. Thus, if one has a saturated fatty acid such as stearic acid and wants to prepare a mono-

11

unsaturated fatty acid which will produce a more soluble soap than stearic acid, one introduces an average of one chlorine atom into the stearic acid molecule. The product will contain an average of one double bond and will be eminently suitable for preparing soap. On the other hand, if it is desired to prepare a drying oil from oleic acid, two or more chlorine atoms are introduced, and then the product will be highly unsaturated and may be used to prepare a drying oil by esterification with glycerine.

The products of the invention may be used in the manufacture of soap or other detergents and in the manufacture of drying oils and plasticizers. Many of the natural fats contain a high proportion of stearic acid. Such fats will not produce a good soap because sodium stearate has low solubility. By hydrolyzing the natural fat, the fatty acids high in stearic acid can be converted by our process into unsaturated derivatives. Such unsaturated fatty acids, when saponified, form soaps much more soluble than stearates and having good surface active properties. Likewise, by chlorinating to a higher degree, compounds having two or more double bonds per molecule can be prepared. These compounds, by reason of their highly unsaturated nature, are eminently suitable for preparing drying oils, and so forth. It has been found that when oleic acid, chlorinated by addition to form chiefly 9,10-dichlorostearic acid, is subjected to dehydrochlorination according to the instant technique, products having two conjugated double bonds are formed. Thus, the products prepared from dichlorinated oleic acid are eminently suitable for preparing drying oils by esterification with glycerol, pentaerythritol, and so forth.

The following examples illustrate some of the uses to which the unsaturated products of this invention may be applied.

EXAMPLE VIII

FOAMING TESTS

A soap was prepared, in the usual manner, from the unsaturated product obtained from dichlorinated palmitic acid (Example 2). This soap was compared with standard soaps according to the technique specified in Bureau of Ships ad interim specifications, 51 S 46 (I. N. T.), December 1, 1943, and 51 D 7 (I. N. T.), November 1, 1942. Expressing the volume produced by coconut oil soap as unity, the following results were obtained:

TABLE IV

Agent	Volume of Foam
Coconut oil soap.....	1
Oleic acid soap.....	1.08
Soap of unsaturated acids obtained from dichlorinated palmitic acid according to this invention.....	1.3

EXAMPLE IX

WETTING TESTS

Tests were made of the relative concentrations of wetting agents in solution required to cause skeins of cotton yarn to sink within a definite time under set conditions. The following results were obtained:

12
TABLE V

Agent	Concentration of Agent
Soap of technical oleic acid.....	1.00
A commercial detergent consisting of a mixture of sodium alkyl benzene sulfonates substantially free from inorganic salts.....	1.03
Soap of unsaturated acids obtained from dichlorinated palmitic acid according to this invention.....	0.81

EXAMPLE X

WASHING TESTS

Swatches of white woolen flannel were soiled and washed according to the specifications referred to in Example VIII. Relative efficiencies of the detergents used were indicated by reflectance measurements made on the washed swatches.

TABLE VI

Agent	Average Reflectance
Unsoiled washed cloth.....	0.607
Soiled cloth.....	0.258
Soiled cloth washed with coconut oil soap.....	0.583
Soiled cloth washed with soap of unsaturated acids obtained from dichlorinated palmitic acid according to this invention.....	0.629

EXAMPLE XI

USE AS DRYING OIL

The unsaturated product obtained from dichlorinated oleic acid (Example V) was esterified with pentaerythritol. The ester was mixed with thinner and japan drier and coated on glass. Upon drying overnight a hard, transparent film was formed on the glass. Similar results were obtained when the unsaturated acid was esterified with a commercial mixture of pentaerythritol and dipentaerythritol.

Having thus described our invention, we claim:

1. A process for dehydrochlorinating a compound selected from the group consisting of high molecular weight chlorinated fatty acids and the alkyl esters thereof, comprising contacting said compound in the vapor phase with a solid dehydrochlorination catalyst selected from the group consisting of the elemental metals vanadium, chromium, iron, cobalt, and nickel, the inorganic compounds of these metals, and mixtures thereof, at a temperature of about from 220° C. to 300° C. and at a pressure below 5 mm. of mercury.
2. A process for dehydrochlorinating a compound selected from the group consisting of high molecular weight chlorinated fatty acids and the alkyl esters thereof, comprising contacting said compound in the vapor phase with a solid, inorganic cobalt compound at a temperature of about from 220° C. to 300° C. and at a pressure below 5 mm. of mercury.
3. A process for dehydrochlorinating a compound selected from the group consisting of high molecular weight chlorinated fatty acids and the alkyl esters thereof, comprising contacting said compound in the vapor phase first with a solid dehydrochlorination catalyst selected from the group consisting of the elemental metals vanadium, chromium, iron, cobalt, and nickel, the inorganic compounds of these metals, and mixtures thereof, in a form having extended surface, and second, with a solid, inorganic cobalt compound supported on a suitable carrier, said

contacting being carried out at a temperature of about from 220° C. to 300° C. and at a pressure below 5 mm. of mercury.

4. A process for dehydrochlorinating a compound selected from the group consisting of high molecular weight chlorinated fatty acids and the alkyl esters thereof, comprising contacting said compound in the vapor phase, first with a chromium-nickel steel alloy in a form having extended surface, and second with a solid, inorganic cobalt compound supported on a suitable carrier, said contacting being carried out at a temperature of about from 220° C. to 300° C. and at a pressure below 5 mm. of mercury.

5. A process for dehydrochlorinating a high molecular weight chlorinated fatty acid, comprising contacting said acid in the vapor phase with a solid dehydrochlorination catalyst selected from the group consisting of the elemental metals vanadium, chromium, iron, cobalt, and nickel, the inorganic compounds of these metals, and mixtures thereof, at a temperature of about from 220° C. to 300° C. and at a pressure below 5 mm. of mercury.

6. A process for dehydrochlorinating a high molecular weight chlorinated fatty acid, comprising contacting said acid in the vapor phase with a solid, inorganic cobalt compound at a temperature of about 220° C. to 300° C. and at a pressure below 5 mm. of mercury.

7. A process for dehydrochlorinating a high molecular weight chlorinated fatty acid, comprising contacting said acid in the vapor phase, first with a solid dehydrochlorination catalyst selected from the group consisting of the elemental metals vanadium, chromium, iron, cobalt, and nickel, the inorganic compounds of these metals, and mixtures thereof, in a form having extended surface, and second with a solid, inorganic cobalt compound supported on a suitable carrier, said contacting being carried out at a temperature of about from 220° C. to 300° C. and at a pressure below 5 mm. of mercury.

8. A process for dehydrochlorinating a high molecular weight chlorinated fatty acid, comprising contacting said acid in the vapor phase, first with a chromium-nickel steel alloy in a form having extended surface, and second with a solid, inorganic cobalt compound supported on a suitable carrier, said contacting being carried out at a temperature of about from 220° C. to 300° C. and at a pressure below 5 mm. of mercury.

9. A process for dehydrochlorinating chlorinated palmitic acid which comprises contacting said acid in the vapor phase with a solid, inorganic cobalt compound at a temperature of about from 220° C. to 300° C. and at a pressure below 2 mm. of mercury.

10. A process for dehydrochlorinating chlorinated palmitic acid which comprises contacting said acid in the vapor phase, first with a chromium-nickel steel alloy in a form having extended surface, and second with a solid, inorganic cobalt compound supported on a suitable carrier, said contacting being carried out at a temperature of about from 220° C. to 300° C. and at a pressure below 2 mm. of mercury.

11. A process for dehydrochlorinating chlorinated palmitic acid which comprises contacting said acid in the vapor phase, first with a chromium-nickel steel alloy in a form having extended

surface, and second with cobalt chloride supported on a suitable carrier, said contacting being carried out at a temperature of about from 220° C. to 330° C. and at a pressure below 2 mm. of mercury.

12. A process for dehydrochlorinating a chlorinated palmitic acid containing an average of 2 atoms of chlorine per molecule, which comprises contacting said acid in the vapor phase, first with a chromium-nickel steel alloy in a form having extended surface, and second with cobalt chloride supported on pumice granules, said contacting being carried out at a temperature of about from 220° C. to 300° C. and at a pressure below 2 mm. of mercury.

13. A process for dehydrochlorinating chlorinated stearic acid which comprises contacting said acid in the vapor phase with a solid, inorganic cobalt compound at a temperature of about from 220° C. to 300° C. and at a pressure below 2 mm. of mercury.

14. A process for dehydrochlorinating chlorinated stearic acid which comprises contacting said acid in the vapor phase, first with a chromium-nickel steel alloy in a form having extended surface, and second with a solid, inorganic cobalt compound supported on a suitable carrier, said contacting being carried out at a temperature of about from 220° C. to 300° C. and at a pressure below 2 mm. of mercury.

15. A process for dehydrochlorinating chlorinated stearic acid which comprises contacting said acid in the vapor phase, first with a chromium-nickel steel alloy in a form having extended surface, and second with cobalt chloride supported on a suitable carrier, said contacting being carried out at a temperature of about from 220° C. to 300° C. and at a pressure below 2 mm. of mercury.

16. A process for dehydrochlorinating a chlorinated stearic acid containing an average of 2 atoms of chlorine per molecule which comprises contacting said acid in the vapor phase, first with a chromium-nickel steel alloy in a form having extended surface, and second with cobalt chloride supported on pumice granules, said contacting being carried out at a temperature of about from 220° C. to 300° C. and at a pressure below 2 mm. of mercury.

17. A process for dehydrochlorinating 9,10-dichlorostearic acid which comprises contacting said acid in the vapor phase, first with a chromium-nickel steel alloy in a form having extended surface, and second with cobalt chloride supported on pumice granules, said contacting being carried out at a temperature of about from 220° C. to 300° C. and at a pressure below 2 mm. of mercury.
